Specification of Letters Patent. Patented Aug, 26, 1913.

Application filed January 16, 1913. Serial No. 742,319.

To all whom it may concern:

Be it known that I, EDWARD STUTZ, a citizen of the Republic of Switzerland, residing at Philadelphia, in the county of 5 Philadelphia and State of Pennsylvania, have invented certain new and useful Improvements in Looms, of which the following is a specification.

This invention is an improvement on that forming the subject of my U. S. Letters Patent No. 960433, wherein is set forth a race for the shuttle in a loom composed of a number of spaced wires forming members which support the shuttle in its passage 15 across the lay or batten and permit the lower threads of the warp shed to fall below the shuttle-supporting surface of said race, so as not to be abraded by the shuttle in its travel. In my said patented construction, although the shuttle-supporting members are made as narrow as possible so as to facilitate the downward entry of the threads between them, a thread occasionally 20 catches and remains supported thereon and thus becomes cut by the shuttle when it travels over the batten. To give the said members sharpened upper edges would obviously be impractical because they would soon be worn broad or flat by the shuttle. 25 According to this invention, the said race has its members formed with properly shaped upwardly projecting parting devices or spurs. These I prefer to place forward of the reed and back of the shuttle's path 30 of travel, and in that case they become useful to afford a back support for the shuttle, keeping it out of contact with and hence preventing its wearing or injuring the dents of the reed. In order that the race, so 35 constructed and arranged, may not interfere with the beating-up function of the reed, I provide means for depressing it so as to bring its spurs aforesaid below the plane of 40 the cloth at the moment of beating-up.

Referring to the accompanying drawings, Figure 1 is a front elevation of a loom constructed in accordance with the present invention, the front portion being removed; Fig. 2 is a plan view showing certain parts 45 in section in a plane below that of the batten; Fig. 3 is a horizontal sectional view of the batten in a plane through the shuttle boxes; Fig. 4 is a longitudinal sectional view of the loom, and, Figs. 5 and 6 show two different forms of shuttle supports.

In the loom frame *a* is arranged to oscillate in the usual manner the batten *b* driven from the crank-shaft *c* through the pitmen *d*. The shuttle *e* is reciprocated from one shuttle box *f* to the other by the usual mechanism including picker-sticks *g*, rock-shafts *h* connected with the picker-sticks by the straps *i*, and tappet-shaft *j* for alternately actuating said rock-shafts, said tappet-shaft being connected with the crank shaft by the 60 gearing *k*.

l is the breast-beam.

The body part *a'* of the batten is a suitable length of material having a longitudinal depression or recess *m* and its ends 70 raised. The depression *m* receives the shuttle-race (to be described) and in order to compensate for the loss of weight thus effected I prefer to make the body part *a'* of the batten of metal, leaving only the shuttle-boxes *f*, which are suitably fitted on the ends of the body part *a'*, of wood. (See Fig. 1.)

The recessed portion of body part *a'* of the batten is penetrated by two vertical rods 80 *n* depending from a horizontal bar *o* and forming therewith a structure adapted to reciprocate vertically, being normally depressed by springs *p* coiled about the rods *n* and interposed between body part *a'* and 85 collars *q* adjustably secured on said rods. The lower ends of the rods are pivotally connected to the front ends of levers *r* having their fulcrum-bolts *s* vertically adjustable in the stands *t* and carrying on their 90 rear ends the shoes *u* adapted to be simultaneously engaged (to rock the levers *r* and raise the rods *n* and bars *o*) by the cams *v* on the tappet-shaft *j*, said shoes being secured to the levers by bolts *w* penetrating 95 longitudinal slots *x* in said levers so as to be adjustable.

The bar *o* carries the aforementioned shuttle-supports which go to form the shuttle-race. These are secured to the bar in spaced 100 relation to each other, extending longitudinally of the warp threads, and each is sufficiently thin so that it may enter between two threads of the warp without undue disturbance thereof; their top surfaces or edges are 105 arranged all in the same horizontal plane and are preferably straight, and said supports are of such height that when they are raised to their upward limit by the bar *o* their said surfaces or edges are flush with 110

the shuttle-supporting surfaces or bottoms of the shuttle boxes *f*. Each has an upstanding sharpened spur or warp-parting projection. Referring to Fig. 5 one such shuttle-support is shown as consisting of a 5 blade *y* having at the rear end thereof the upstanding tapered portion *z* forming the aforesaid warp-parting projection or spur; in Fig. 6 the shuttle support comprises the strip *2* having the integral upstanding tapered portion *3* (to form said spur or projection) and the angular wire *4* fitted at its ends into said strip and the portion *3*. In each instance, a downwardly projecting flat 10 tail or lug *5* is provided whereby, by a bolt *6* passed through it and the bar *o*, the shuttle-support is removably secured to said bar. As will be explained, the reed is set back in the batten so that its front face is not (as is usually the case) flush with the back surfaces of the shuttle boxes. The reed is 15 therefore not subjected to the wearing contact of the shuttle in its passage across the batten, but instead the shuttle is supported at the back by the spurs or projections of the shuttle-supports, which for this purpose preferably have broad flat front faces (Figs. 5 and 6) arranged flush with the back surfaces of the shuttle boxes.

20 The reed, designated *7*, is supported thus: A substantially U-shaped frame *8* is secured by its lateral ears *9* to the upper ends of the lay-swords *10* carrying the batten *b*, and the horizontal bar-portion *8'* of this frame 25 forms one part of a clamp for the lower edge of the reed, the other part of such clamp being the bar *12* pressed toward bar *8'* by the springs *13* interposed between bar *12* and pins *14* set in the ends of studs *15* 30 projecting rearwardly from bar *8'* through bar *12*. At the top of frame *8* is secured a cross-bar *16* slotted on its under side. The upper edge of the reed being entered into the slotted bar *16*, its lower edge is fitted between the bars *8'* and *12* and held by their 35 clamping action.

17 designates angle brackets to support the frame *8* against backward displacement when the reed comes against the cloth.

40 Operation: When the warp shed is open and the shuttle is thrown across the batten in the usual manner the series of shuttle-supports stand with their top surfaces flush with the bottom surfaces of the shuttle-boxes, to which position they have been 45 raised by the bar *o* under actuation from the cams *v*. The lower warp-threads of the shed have been parted at intervals by the spurs or projections of the said shuttle-supports, and the race formed by the top surfaces of said shuttle-supports stands somewhat higher than the plane of said threads (dotted lines, Fig. 4). The shuttle, when thrown, therefore travels through the shed 50 without contacting with and abrading or

cutting said threads; and in its passage it is supported at the back by said spurs or projections, thus saving the dents of the reed from the wear to which they are usually subjected. When the batten swings forward the cams *v* clear the shoes *u* of levers *r*, 70 allowing the springs *p* to depress the series of shuttle-supports (the shuttle being now boxed) so as to move their spurs or projections out of interposed relation to the reed and the cloth and allow the reed to beat up the filling to the fell of the cloth. 75

Having thus fully described my invention, what I claim as new and desire to secure by Letters Patent is:

1. In combination, the batten-structure including the shuttle boxes, the reed and the shuttle, said batten-structure having a shuttle-race disposed between said boxes and including spaced shuttle-supports arranged in a series extending longitudinally of the batten and each support having an upwardly tapering warp-dividing projection extending upwardly from the shuttle-supporting surface thereof, substantially as described. 85

2. In combination, the batten-structure including the shuttle-boxes, the reed and the shuttle, said batten-structure having a shuttle-race disposed between said boxes and including spaced shuttle-supports arranged in a series extending longitudinally of the batten and each support having an upwardly tapering warp-dividing and shuttle-supporting projection extending upwardly from the shuttle-supporting surface of said support and forward of the reed, substantially as described. 95

3. In combination, with a batten-structure including the shuttle-boxes, the reed and the shuttle, said batten-structure having a shuttle-race disposed between said boxes and movable downwardly from a position where its shuttle-supporting surface is flush with the bottom-surfaces of said boxes, means for moving the batten back and forth, and means for moving the shuttle-race up and down, substantially as described. 105

4. In combination, with a batten-structure including the shuttle-boxes, the reed and the shuttle, said batten-structure having a shuttle-race disposed between said boxes and movable downwardly from a position where its shuttle-supporting surface is flush with the bottom-surfaces of said boxes, said shuttle-race comprising spaced warp-dividing 115 shuttle-supporting portions arranged in a series extending longitudinally of the batten structure, means for moving the batten back and forth, and means for moving the shuttle-race up and down, substantially as described. 120

5. In combination, with a batten-structure including the shuttle-boxes, the reed and the shuttle, said batten-structure having a shuttle-race disposed between said boxes and 125

movable downwardly from a position where its shuttle-supporting surface is flush with the bottom-surfaces of said boxes, said shuttle-race comprising spaced shuttle-supporting portions arranged in a series extending longitudinally of the batten-structure, and having upstanding warp-dividing projections, means for moving the batten back and forth, and means for moving the shuttle-

race up and down, substantially as described.

In testimony whereof I affix my signature in presence of two witnesses.

EDWARD STUTZ.
